United States Patent Office.

DUNHAM WILKES, OF NINEVEH, INDIANA.

Letters Patent No. 99,507, dated February 1, 1870.

IMPROVEMENT IN SHINGLE-MACHINE.

The Schedule referred to in these Letters Patent and making part of the same.

To all whom it may concern:

Be it known that I, DUNHAM WILKES, of Nineveh, in the county of Johnson, and State of Indiana, have invented a new and useful Portable Shingle-Machine; and I do hereby declare the following to be a full, clear, and exact description of the same, sufficient to enable others skilled in the art to which my invention appertains to make and use the same, reference being had to the accompanying drawings, forming part of this specification, in which—

Figure 1 is a front view of the device illustrating my invention.

Figure 2 is a sectional plan view in the line *z z*, fig. 2.

Similar letters of reference indicate corresponding parts in the two figures.

My invention relates to an arrangement of the gearing of a portable shingle-machine, as hereinafter more fully set forth.

In the drawings—

A A' represent the sill-pieces, to which are secured uprights B, which are connected together at the top by a cap or cross-piece, C.

D represents a table or platform, which is secured to the uprights, and intended to support the timber while being presented to the knife.

A shaft, E, is mounted on the sill A', and carries on one end a crank or crank-wheel, a, to which is connected a pitman, b, which is joined to the lower end of a sliding frame, F, which carries a knife, G, and gauge H.

A toothed wheel, c, is mounted on the shaft E, which gears with a pinion, d, mounted on the driving-shaft J, whose bearings, on one side, are on an arch or frame, K, which is elevated above the sill A'', and the other side is on an auxiliary upright, B', extending parallel with the upright B.

The shaft J also carries the fly-wheel w and pulley e, the former of which revolves between the cross-pieces B B'.

A staple, L, is hinged to each end of the sills A A', said staples being of ordinary construction and form.

It will be seen that the frame and working-parts, as thus described, form a portable device, which, when carried to any intended spot, may be firmly held in place, by driving wedges or stakes through the staples against the ends of the sills.

The frame F slides between the uprights B and the knife G, which is secured to said sliding frame F, has a cutting-edge of two diagonal faces, which are brought down against and cut through the timber when the frame is lowered, through the medium of the operating-mechanism.

The gauge H consists of a flat plate of metal, extending in line with the knife G, and formed with ears

or lugs, through which passes a pivot-rod, M, whose ends enter the eyes of screw-bolts N, which are supported and guided in block O, secured respectively to the middle and lower cross-pieces of the frame F.

These screw-bolts are readily operated through the medium of screw-nuts or taps n, working on the blocks, and allowing the gauge to be set relatively to the thicknesses of the shingle to the cut.

The gauge is to be adjusted relatively to the set or taper of the shingle, by means of screws P, which pass through the middle cross-bar, and bear against the ends of the gauge.

The operation is as follows:

The timber is split into broad blocks, from four to eight inches thick, and from six to eighteen broad, owing to the size of the timber, the broad part of the block being split across the grain of the timber, so that the grain or splitting way of the timber is across the block in the thin way.

After the timber has been well steamed, a block is placed on the table with the edge down, from which he intends to begin to cut the shingles.

As the knife ascends, the operator slips the broad side of the block under the knife. As it descends, he takes off a thin slip, barely sufficient to face the block and make the shingle straight. It is then placed, with the face side down, on the table, and the edge from which he intends to cut the shingles, as the knife ascends, is slipped under and faced. The block is here set up on the faced edge, and the other side faced, as before, and the block is now ready to be cut into shingles. The operator now observes the grain of the timber at the edge of the block, and places that side of the block down, which causes the grain at the edge of the block to tend slightly to the knife downward, and then takes hold on each end of the block, and, as the knife ascends, he slides it against the gauge-bearing, at each stroke of the knife, sufficiently hard, first with right hand and then with left, to turn the gauge, making the thick end of the shingle first at one end and then at the other, until the block is cut up, unless the grain of the timber begins to run with the edge of the knife, or tend toward the block downward; then the block must be turned bottom side up, with the same edge to the knife, which sets the grain right with the knife, and the block is finished, as previously described. I will remark, that so long as this rule of keeping the grain of the timber tending slightly toward the knife downward, the shingles will always be as solid as if sawed or shaved; but if the grain in the wood begins to run with the edge of the knife, or tend into the block downward, it begins to come in line with the face of the back part of the knife, which is bevelled or wedge-shaped, and begins to draw into the block, and crack or spoil the shingles. On the con-

trary, when the grain of the timber is tending slightly toward the knife downward, the front face of the knife being straight, it cuts smoothly through the block without drawing the knife, and the grain of the timber in the shingle, as it comes off, stands bracing toward the knife, and will not curl from the knife, but will come off solid and true. For this reason, I attach no feeding-apparatus to my machine.

The screws *N* are designed to move the gauge in or out, to suit the thickness of the shingle, and the screws *P* can be set in against the end of the gauge, so as to prevent it from turning on its pivot, and make straight shingles, if desired. Experienced operators can use it in this way for jointing the timber before cutting into shingles.

Having thus described my invention, What I claim as new, and desire to secure by Letters Patent, is—

The arrangement of gearing *c d*, shafts *E J*, elevated bearing *K*, fly-wheel *w*, and pulley *e*, in connection with knife *G*, and gauge *H*, uprights *B B'*, sills *A A'*, and staples *L*, to form a portable shingle-machine, as described.

The above, signed by me, this 20th day of July, 1869.
DUNHAM WILKES.
